UNITED STATES PATENT OFFICE

BENJAMIN C. BARTLEBAUGH, OF WHEELING, WEST VIRGINIA

GAS HEATER

Application filed January 7, 1931. Serial No. 507,259.

The invention relates to improvements in gas heaters of the so-called burn-over type, in which all unburned gas escaping from the burner, is mixed with fresh air and directed to the jets of flame exuding from said burner, so that they will be consumed, instead of escaping to the room and fouling the air as well as charging it with a dangerous gas content.

10 Heaters of the general type above mentioned, are shown in my U. S. Patents 1,110,867 of September 15, 1914, 1,298,277 of March 25, 1919, and 1,563,890 of January 1, 1925. While all of these prior structures have possessed a rather high state of efficiency, I have discovered that better results are obtainable if the velocities of the hot gases ascending from the burner and the air entering from the front of the heater, be increased so that 20 they will mix and be conducted into the burner flame with less drop in temperature of said gases, and I have succeeded in producing a new and improved structure in which the requisite high velocities of ascending gases and incoming air are attained, the object of the present application being to protect this improved structure.

With the foregoing in view, the invention resides in the novel subject matter hereinabove described and claimed, description being accomplished by reference to the accompanying drawings.

Fig. 1 is a perspective view of a heater constructed in accordance with my invention.

35 Fig. 2 is a vertical longitudinal sectional view on line 2—2 of Fig. 3.

Fig. 3 is a vertical transverse sectional view on line 3—3 of Fig. 2.

Fig. 4 is a horizontal sectional view on line 40 4—4 of Fig. 3.

Figs. 5, 6 and 7 are perspective views of parts hereinafter described.

The drawings above briefly described, illustrate a preferred construction, and while 45 this construction will be specifically explained, it is to be understood that within the scope of the invention as claimed, minor variations may be made.

The heater embodies a casing 8 having 50 vertical front and rear walls 9 and 10 and

vertical end walls 11, said casing being provided with a top 12 which is arched from front to rear on a curved line merging into said front and back walls, leaving the inner side of said top with no portions which can interfere with free and rapid travel of air, as will be hereinafter further explained. The front wall 9 is provided with an opening 13 and with a sill 14 projecting rearwardly from the lower edge of said opening, and the lower portions of the end walls 11, are formed with air-admission openings 15. A burner-supporting plate 16 is secured to and projects rearwardly from the sill 14, and a horizontally elongated burner 17 is supported by said plate 16, being provided with appropriate gas-conducting piping 18 and air-mixers 19.

A vertical longitudinal fire wall 20 is secured in the casing 8 and projects upwardly 70 from the rear portion of the burner 17, said fire wall being provided with a free upper end 21 downwardly spaced from the casing top 12. The lower portion of the fire wall 20 is preferably offset forwardly as shown, and said lower wall portion is provided with a row of air-conducting perforations 22 disposed near the upper extremity of the burner 17. Behind the burner and the lower portion of the wall 20, is a baffle 23 which inclines forwardly, the upper end of said baffle being free, being spaced rearwardly from the burner and wall, and being downwardly spaced from the perforations 22. Air entering the casing through the openings 15 is guided by the baffle 23 toward said perforations 22.

80 A vertical longitudinal partition 24 is secured in the casing 8 between the rear wall 10 of the latter and the fire wall 20, being spaced from both of these parts 10 and 20. The partition 24 is provided with a free lower end 85 25 spaced horizontally rearward from the perforations 22, and the upper end of said partition 24 is provided with a cowl 26 which is transversely curved and preferably about concentric with the casing top 12. This cowl 26 is inwardly spaced from the casing top 12 and is provided with a free front end 27 spaced rearwardly from the upper end of the 90 95 100

opening 13. Hence, a channel 28 is provided between the cowl 26 and the casing top 12 and between the partition 24 and the rear casing wall 10 for the purpose of conducting the air which enters through the opening 13, the travel of this air being indicated by the various arrows 29. Due to the curvature of the cowl 26 and casing top 12, they offer no obstruction to the travel of this air and hence it can take place much more rapidly than in the prior heaters above mentioned. Moreover, the hot ascending gases indicated by the arrows 30 as rising from the burner 17, will be caught by the cowl 26 and directed rearwardly and downwardly without resistance, so that they flow more rapidly behind the fire wall 20. These hot unburned gases rapidly mix with the heated air discharged from the passage 28, and the mixture of gases and air blows forwardly through the perforations 22, with considerable force, so that said mixture is directed under pressure into the flame ascending from the burner 17, insuring combustion of previously unburned fuel units. This "burn-over" operation continues uninterruptedly as long as the heater is being used and consequently the latter will emit no obnoxious odors and no dangerous gases. While my prior heaters have operated in this same general way, the construction herein disclosed constitutes a great improvement, in that the air and gases flowing as indicated by the arrows 29 and 30 are not resisted, the lack of resistance being due primarily to the shape of the cowl 26 and the casing top 12. Another element of the improved structure which I believe to be of importance in attaining the better results, is the baffle 23 which directs a quantity of fresh air entering through the openings 15 toward the perforations 22 as indicated by the arrows 31, to mix with the heated air from the passage 28 and with the hot gases flowing downward behind the fire wall 20, the mixture flowing with considerable force through said perforations 22.

Attention is invited to the fact that the construction is such as to apply the flame of the burner to the returned unburnt gas, thereby destroying the poison and unpleasant odors. The offset in the fire wall contributes in obtaining this result, as the flame cannot play upon said fire wall. It is known that where the gas flame strikes iron or any object, poison gases and unpleasant odors are given off from the gas fire.

I claim:-

1. A gas heater comprising a casing comprising front, back and end walls and a top arched from front to rear on a curved line merging into said front and back walls, said front wall having an opening, a horizontally elongated burner mounted longitudinally in said casing near the lower end of said opening, a longitudinal fire wall extending upwardly from the rear portion of said burner,

spaced forwardly from said rear casing wall and spaced downwardly from said arched casing top, said fire wall having a free upper end having air perforations near the upper extremity of the burner, and a vertical longitudinal partition in said casing disposed between and spaced from said back wall and said fire wall, the lower end of said partition being free and extending downwardly as far as said perforations of said fire wall, the upper end of said partition being provided with a forwardly projecting transversely curved cowl spaced upwardly from said fire wall and spaced inwardly from said arched top, the rear portion of said cowl merging into said partition and the front end of said cowl being free.

2. A gas heater comprising a casing comprising front, back and end walls and a top arched from front to rear on a curved line merging into said front and back walls, said front wall having an air admitting opening, the lower portion of said casing being provided with air admission means, a horizontally elongated burner mounted longitudinally in said casing behind the front wall thereof, a longitudinal fire wall extending upwardly from the rear portion of said burner, spaced forwardly from said rear casing wall and spaced downwardly from said arched casing top, said fire wall having a free upper end and having air perforations in its lower portion disposed near the upper extremity of the burner, a baffle wall behind said burner inclining forwardly toward said fire wall and having a free upper end spaced downwardly from said air perforations and spaced rearwardly from said fire wall, and a vertical longitudinal partition in said casing disposed between and spaced from said back wall and said fire wall, the lower end of said partition being free, the upper end of said partition being provided with a transversely curved forwardly projecting cowl spaced upwardly from said fire wall and spaced inwardly from said arched top, the rear portion of said cowl merging into the upper end of said partition and the front end of said cowl being free.

In testimony whereof I affix my signature.

BENJAMIN C. BARTLEBAUGH.
